Patented Oct. 12, 1971

222,277

BOOT RACK

Ralph Kraus, 262 Central Park W.,
New York, N.Y. 10024

Filed May 8, 1970, Ser. No. 22,887

Term of patent 14 years

Int. Cl. D6—01

U.S. Cl. D33—3

FIG. 1

FIG. 2

FIG. 3

FIG. 1 is a top plan view of a boot rack showing my new design;

FIG. 2 is a front elevational view thereof; and

FIG. 3 is a side elevational view thereof.

I claim:

The ornamental design for a boot rack, as shown.
